(57) **CLAIM**

The ornamental design for a waterproof electronics container, as shown and described.

DESCRIPTION

FIG. 1 is an isometric view of a waterproof electronics container illustrating a lid portion, a console portion, a separator portion, and a container portion in juxtaposition with each other and broken lines to demonstrate how each piece is compiled to configure the waterproof electronics container; FIG. 2 is an isometric view of the lid portion; FIG. 3 is front view of FIG. 2; FIG. 4 is a rear view of FIG. 2; FIG. 5 is a left-hand side view of FIG. 2; FIG. 6 is a right-hand side view of FIG. 2; FIG. 7 is a top view of FIG. 2; FIG. 8 is a bottom view of FIG. 2; FIG. 9 is an isometric view of the console portion; FIG. 10 is a front view of FIG. 9, wherein a rear view is a mirror image of the front view; FIG. 11 is a left-hand side view of FIG. 9, wherein a right-hand side view is a mirror image of the left-hand side view; FIG. 12 is a top view of FIG. 9; FIG. 13 is a bottom view of FIG. 9; FIG. 14 is an isometric view of the separator portion; FIG. 15 is a front view of FIG. 14, wherein a rear view is a mirror image of the front view; FIG. 16 is a left-hand side view of FIG. 14, wherein a right-hand side view is a mirror image of the left-hand side view; FIG. 17 is a top view of FIG. 14, wherein a bottom view is a mirror image of the top view; FIG. 18 is an isometric view of the container portion; FIG. 19 is a front view of FIG. 18; FIG. 20 is a rear view of FIG. 18; FIG. 21 is a left-hand side view of FIG. 18, wherein a right-hand side view is a mirror image of the left-hand side view; FIG. 22 is a top view of FIG. 18; FIG. 23 is a bottom view of FIG. 18; and, FIG. 24 is another isometric view of the waterproof electronics container with the lid portion, console portion, screen portion, and container portion compiled together. The broken lines illustrate portions of the waterproof electronics container which form no part of the claimed design.
